(57) **CLAIM**

The ornamental design for a lunch-bag, as shown and described.

DESCRIPTION

FIG. 1 is a perspective view of a lunch-bag, in accordance with the present design, shown in a flattened condition;

FIG. 2 is a front elevational view of the lunch-bag of FIG. 1, the rear elevational view being a mirror image of the front elevational view;

FIG. 3 is a right side elevational view of the lunch-bag of FIGS. 1 and 2;

FIG. 4 is a left side elevational view of the lunch-bag of FIGS. 1-3;

FIG. 5 is a top plan view of the lunch-bag of FIGS. 1-4;

FIG. 6 is a bottom plan view of the lunch-bag of FIGS. 1-5;

FIG. 7 is a perspective view of the lunch-bag of FIGS. 1-6, shown in an expanded condition containing totable items therein;

FIG. 8 is a front elevational view of the lunch-bag of FIG. 7, the rear elevational view being a mirror image of the front plan view;

FIG. 9 is a right side elevational view of the lunch-bag of FIGS. 7 and 8;

FIG. 10 is a left side elevational view of the lunch-bag of FIGS. 7-9, having a totable item in the form of a bottle, shown in phantom, disposed therein;

FIG. 11 is a top plan view of the lunch-bag of FIGS. 7-10, having a totable item in the form of a bottle, shown in phantom, disposed therein;

FIG. 12 is a bottom plan view of the lunch-bag of FIGS. 7-11; and,

FIG. 13 is a front elevational view of the lunch-bag of FIGS. 1-12, illustrating a compartment thereof in an open condition and having a totable item in the form of a container, shown in phantom, disposed therein.

Items shown in phantom are for illustrative purposes only and do not constitute a part of the claimed design.
